UNITED STATES PATENT OFFICE.

ARTHUR G. G. GUENTHER, OF CHICAGO, ILLINOIS, ASSIGNOR TO SIGNODE SYSTEM INC., OF CHICAGO, ILLINOIS, A CORPORATION OF DELAWARE.

MACHINE FOR APPLYING BOX STRAPS.

Application filed April 5, 1920. Serial No. 371,264.

To all whom it may concern:

Be it known that I, ARTHUR G. G. GUENTHER, a citizen of the United States, residing at Chicago, in the county of Cook, State of Illinois, have invented an Improvement in a Machine for Applying Box Straps, of which the following is a specification.

This invention relates to means for facilitating the application of tensional bindings to boxes and packages and particularly to a strapping bench, whereby tensional box strapping may be applied, for reinforcing purposes to such boxes and packages.

It is the object of the invention to produce a construction of the character described, simple and economical in construction and efficient in operation. Other objects and advantages of the invention will appear as the description to follow proceeds.

Fig. 1 is a plan view of the strapping bench.

Fig. 2 is a sectional elevation thereof on the line 2—2 of Fig. 1.

Upon reference to the drawings it will be observed that there is provided, first, a platform 1 equipped with rollers 2, along which a box or package may be trundled; and that located about midway of the platform 1 and at the rear side thereof is a reel 2^a for box strapping 3. Referring to Fig. 2, (and assuming a box to be in the position indicated in dotted lines), the strapping 3 is fed endwise from the reel, down the rear leg 4 of a collapsible U-shaped channel iron strap guide. The rear leg 4 of this guide passes down below the plane of the rollers and then forwardly as indicated at 5, while the front leg 6 has a horizontally and rearwardly directed lower end 7, which is telescoped within the forwardly extending portion 5 of the rear leg 4, just referred to.

This construction affords a collapsible U-shaped guide, of channel form in cross section, which guides the strapping fed endwise thereinto, down the rear side of the box or package, under the bottom thereof and up the front side, whereupon it can be overlapped, stretched, and sealed on the top of the box by the operator.

It is desirable to compress certain types of boxes and packages during the application of tensional binders thereto. It is efficient to apply the compression at the point where the binder is put on. I provide a treadle 8, which by suitable connections,

hereinafter more specifically described, may be depressed to force the rear leg 4 of the collapsible U-shaped strap guide forwardly, squeezing the box between the two legs of the guide, thus applying compression upon the box at precisely the point where it is desired to apply the strapping.

Having pointed out briefly the more important operating elements of the machine, I shall now describe the construction in detail.

The platform 1 is formed of angle iron 9 and channel iron 10 (Fig. 2) and is rigidly supported upon the legs 11. In the front and rear frame members of this platform are mounted the rollers 2 in any suitable manner, as by having their axles seated in half bearings not shown.

The front leg 6 of the collapsible U-shaped strap guide is firmly mounted upon the front frame member 10, a brace 12 being secured upon that member for rigidity. The rear leg 4 of the U-shaped strap guide is secured in a casting 13 which is in turn secured to an angle plate 14, from which depend at a substantial distance from each other the two carriages 16, each of which is apertured to receive, and slides on the rods 17, which are bolted as indicated at 18 across the platform, parallel to, between and below the plane of the rollers. It has been pointed out that the U-shaped strap guide is collapsible, the horizontal parts 5—7 thereof being telescoped. It will be clear that the rear leg 4 thereof being slideable along the rods 17 may be brought forward or retracted in the plane of a binder and at right angles to the travel of the box as it is trundled through the machine.

The treadle 8 through which the rear strap guide 4 is moved forwardly swings on the pivot 20 having bearings in a bracket 21, secured to the rear angle iron 9, the curved arms 21, connecting the treadle with its pivot. Pivotaly mounted on the curved arms 21, at the point 22, are sheaves 23. A rope 24 which passes through apertures in the front channel frame member 10 and is provided with knots 24', passes through the sheaves 23, then over idlers 25, secured in brackets 26 inside of the front frame channel member, is looped through holes in the angle plate 14. The angle plate 14 being slideable forward and back upon the rods 17, by means of carriages 16 and carrying

the rear leg 4 of the U-shaped strap guide, it will be apparent that pressing downwardly on treadle 8 will serve to squeeze the box or package with considerable force between 5 the two legs 4 and 6 of the U-shaped strap guide.

Means are provided for holding the rear leg 4 of the strap guide normally back in the position shown in Fig. 2 and thus to permit 10 the free passage of the box or package through the machine. Thus a long leaf spring 30 is slidably secured at either end to the rear legs 11 of the machine, and clamped at its central portion by means of 15 the bolt 31 in the hook 32, on the bracket 33, which at its rear end extends upwardly and is secured to the angle iron 9 forming the rear frame work of the platform. This spring clearly serves normally to hold the 20 rear leg of the U-shaped guide in its retracted position.

For supporting the reel 2, I provide a stand 34, suitably secured to the rear frame angle iron 9, from which extends upwardly 25 a support 35 carrying an upper table 36, across which the strap passes from the reel 2 to the box or package, and upon which it may be inspected. The table 36 is provided with spaced apertures through which are 30 dropped the legs of a heavy staple-like member 37 which thus rests upon the strap and serves to tension and steady its feed.

In operation, a box or package is trundled along the platform until the portion of it 35 to which it is desired to apply the binder is located between the front and rear legs of the U-shaped strap guide. Thereupon the treadle is depressed and the box or package heavily squeezed between the front and 40 rear channel members of the U-shaped guide, the strapping is then drawn off from the reel and pushed downwardly in the channel of the rear leg 4 of the strap guide, the U-shaped strap guide directs the strapping down around the bottom of the box or package and up the front side thereof where it 45 may be overlapped, stretched and joined. After this the strapping is broken off, the treadle 8 is permitted to rise, releasing the 50 box or package, which is then trundled along the platform. It will be apparent that boxes having a wide variety of girths may be handled on the same machine, and that the pressure applied to compress the 55 box is under the control of the operator. Thus if desired the strap guide may merely be closed upon a box or package in order accurately to direct the strap thereabout, without the application of substantial pressure thereto. The fact that the guide functions with equal efficiency upon boxes and 60 packages of widely varying girths is equivalent to adjustability in the guide, but does not require an adjustment (in the proper 65 sense) of the machine. In this sense the

guide may be temporarily adjusted during each operation. An adjustment proper however is easily effected to cause the strap guide to function efficiently on boxes or packages of any size, from the largest the 70 machine will take, to those of very small size. This adjustment may be effected by shortening the rope 24, by knotting it further from one of its free ends as is shown at 24'; (Fig. 2); which will leave the parts 75 in the same position but elevate the treadle and thus give the guide a greater throw i. e., permit its rear leg to be moved further forward upon the maximum depression of the treadle.

Having described my invention, I claim:

1. A strapping bench for applying tensional binders to boxes and packages, comprising in combination, means for supporting a box or package during the strapping operation, a guide extending around two corners of the box and adapted to pass the banding material around said corners when the same is fed endwise into the guide, and manually operated means for bringing said 90 guide into forcible engagement with said box or package so as to apply its whole force at points immediately adjacent to the place where the binder is to be applied.

2. A strapping bench for applying tensional binders to boxes and packages, comprising in combination, means for supporting a box or package during the strapping operation, a guide for banding material adapted to direct said material around three sides of the box when said banding material is fed endwise into the guide; and means for adjusting the space between opposite sides of said guide to engage boxes or packages of varying widths on the opposite sides thereof.

3. A strapping bench for applying tensional binders to boxes and packages, comprising in combination, means for supporting a box or package during the strapping operation, a guide for banding material adapted to direct the same around the two sides and bottom of the box when said banding material is fed endwise into the guide, said guide being formed of a plurality of sections telescoping together and means for causing one side of said guide to approach the opposite side so as to forcibly engage therebetween boxes of varying widths.

4. A strapping bench for applying tensional binders to boxes and packages, comprising in combination, means for supporting a box or package during the strapping operation, a guide for banding material adapted to direct the same around corners of the box when said banding material is fed endwise into the guide, said guide being formed of a plurality of sections telescoping together whereby boxes of different 130

sizes may be accommodated, resilient means for holding said guide sections in normally predetermined relationship, and means under the sole control of the operator for 5 selectively moving one side of said guide so as to forcibly engage boxes of varying widths.

5. A strapping appliance for facilitating the application of tensional binders to boxes 10 and packages comprising a pathway along which boxes or packages may be moved, a U-shaped guide arranged transversely across the pathway and adapted to enclose a plurality of sides of the box or package, said 15 guide being adapted to direct a tensional binder fed endwise thereinto, around a plurality of corners of the box.

6. A strapping appliance for facilitating the application of tensional binders to boxes 20 and packages comprising a pathway along which boxes or packages may be moved, a U-shaped guide arranged transversely across the pathway and adapted to enclose a plurality of sides of the box or package, said 25 guide being adapted to direct a tensional binder fed endwise thereinto around a plurality of corners of the box, and a reel located adjacent one end of the U-shaped guide to feed tensional binding material conveniently thereinto.

7. An appliance of the character described, comprising a strap guide adapted partially to enclose an appropriately positioned box or package, means for causing 25 said guide to contact with certain sides of boxes or packages of varying dimensions on each operation without an adjustment of the machine.

8. An appliance of the character described, comprising a strap guide adapted 40 partially to enclose an appropriately positioned box or package, said strap guide being adapted to be telescoped to bring certain of its sides together, and means for telescoping the strap guide whereby the same may be utilized to function uniformly upon boxes 45 and packages of varying sizes.

9. An appliance of the character described, comprising a strap guide adapted 50 partially to enclose an appropriately positioned box or package, said strap guide being adapted to be telescoped to bring certain of its sides together, and means for telescoping the strap guide whereby the same 55 may be utilized to function uniformly upon boxes and packages of varying sizes, and tension means for causing said strap guide to return to normal position.

10. An appliance of the character described, comprising a strap guide adapted 60 partially to enclose an appropriately positioned box or package, means whereby said strap guide may be contracted to bring certain of its sides into proximity to those of a 65 box or package.

11. An appliance of the character described, comprising a strap guide adapted partially to enclose an appropriately positioned box or package, means whereby said strap guide may be contracted to bring certain of its sides into proximity to those of a box or package and means to cause said 70 guide to return to its normal position after such contraction.

12. An appliance of the character described, comprising a strap guide adapted 75 partially to enclose an appropriately positioned box or package, means whereby said strap guide may be contracted to bring certain of its sides into proximity to those of a 80 box or package and means whereby the throw of the strap guide in its contracting movement may be adjusted.

13. An appliance of the character described, comprising a strap guide adapted 85 partially to enclose an appropriately positioned box or package, means whereby said strap guide may be contracted upon boxes or packages of varying dimensions to effect 90 a temporary adjustment thereof in each operation to accommodate the particular box or package, means to cause said guide to resume its predetermined position after each operation, and means whereby the range of 95 said temporary adjustment may be varied for an indefinite succession of operations.

14. An appliance of the character described, comprising a strap guide adapted partially to enclose an appropriately positioned box or package, said strap guide comprising two guiding members, and means under the sole control of the operator for 100 variously adjusting the space between said guiding members.

15. An appliance of the character described, comprising a strap guide adapted 105 partially to enclose an appropriately positioned box or package, said strap guide comprising open channel members, means for moving said channel members into contact with the box or package on their open side, thus providing a closed pathway for 110 the strap.

16. An appliance for facilitating the application of tensional binding material to 115 boxes or the like, comprising a support a guide adapted to direct tensional banding material around a box located on the support, where said material is fed endwise thereinto, said guide having parts facing 120 opposite sides of the box, and means for moving said parts toward each other, whereby the guide may be operated to compress the box during the application of reinforcing finder material thereto.

17. An appliance for facilitating the application of tensional binding material to 125 boxes or the like, comprising a support a guide providing an open channel to receive the binder material adapted to direct ten- 130

10 sional banding material around a box located on the support, where said material is fed endwise thereinto, said guide providing an open channel to receive the 5 binder material and having parts facing opposite sides of the box, and means for moving said parts toward each other, whereby the guide may be operated to compress the box during the application of reinforcing 10 binder material thereto.

15 18. An appliance for facilitating the application of tensional binding material to boxes or the like, comprising a support, a guide, adapted to direct tensional banding material around a box located on the support, when said material is fed endwise thereinto, said guide having parts facing opposite sides of the box, and treadle operated means for moving said parts toward 20 each other whereby the guide may be operated to compress the box during the operation of applying reinforcing binder material thereto.

25 19. An appliance for applying a tensional binder to a box or package comprising in combination a guide for the banding material and means acting through said guide to exert compressive force on the box or package during the process of ap-

plying the binder thereto, whereby the compressive force may be localized and applied at the point where the banding material is applied. 30

20. A strapping appliance for facilitating the application of tensional banding material to boxes and packages, comprising a roller trackway along which boxes or packages may be trundled, a channel guide for banding material arranged to pass under a box or package on said trackway and to 40 direct banding material, fed endwise into said guide, around the box or package, said guide having two sides normally spaced apart sufficiently to permit the box or package to pass between them and having a 45 telescoping bottom section, whereby the said sides may move toward and away from each other, without interfering with the continuity of the path for banding material established by the guide, a treadle and connections for causing the two sides of said guide to move together to contact with and exert pressure on two sides of the box or package, and resilient means causing said two sides to recover their normal position. 50

In testimony whereof, I have signed my name to this specification.

ARTHUR G. G. GUENTHER.
